UNITED STATES PATENT OFFICE.

MATTHEW J. BOGERT, OF DEMAREST, NEW JERSEY.

DESIGN FOR A BOX.

SPECIFICATION forming part of Design No. 21,303, dated January 19, 1892.

Application filed December 11, 1891. Serial No. 414,738. Term of patent 7 years.

To all whom it may concern:

Be it known that I, MATTHEW J. BOGERT, a citizen of the United States, residing at Demarest, in the county of Bergen and State 5 of New Jersey, have invented and produced a new and original Design for a Box; and I do hereby declare the following to be a full, clear, and exact description of the same, reference being had to the accompanying representation, forming a part thereof.

My invention relates to a new and original design for boxes; and it consists in the peculiar configuration of the same, as hereinabove disclosed, and pointed out in the claim.

15 In the accompanying illustration, Figure 1 is a side view of my original design, and Fig. 2 is a sectional view thereof.

A is the body of the box, in its general contour cylindric and ornamented with a series 20 or plurality of flat plain-surfaced bands a, separated by a series of slight interstices or grooves a' throughout the top band encompassing the cover B. The cover has a central diminutive knob-like terminal b upon 25 its upper side, and is stepped, as at b', upon its lower or inner side, with said stepped por-

tion fitting in a separate receptacle presently referred to. The band a next to the top or cover forms the upper edge of an inner receptacle c, fitting within the body of the box. 30

C is the base or foot, of disk-like contour, connected with the body of a box by a cylindric stem or leg d, having centrally of the base or body a circular enlargement, forming a ring-like configuration d' thereon. 35

Having thus fully described my invention, what I claim as new, and desire to secure by Letters Patent, is—

The design for a box herein shown and described, having a cylindric body encompassed 40 by a series of plain flat-surfaced rings, with separating slight interstices or grooves, a central knob-like terminal on its cover, and its base connected to its body by a cylindric stem or leg having a central enlargement or ring. 45

In testimony whereof I affix my signature in presence of two witnesses.

MATTHEW J. BOGERT.
